UNITED STATES PATENT OFFICE.

GEORGE W. TEASDALE, OF ST. LOUIS, MISSOURI.

DISAPPEARING BED.

1,293,978.

Specification of Letters Patent.

Patented Feb. 11, 1919.

Application filed February 19, 1917. Serial No. 149,540.

To all whom it may concern:

Be it known that I, GEORGE W. TEASDALE, a citizen of the United States, residing at St. Louis, Missouri, have invented a certain new and useful Improvement in Disappearing Beds, of which the following is a full, clear, and exact description, such as will enable others skilled in the art to which it appertains to make and use the same.

10 This invention relates to beds of the so-called disappearing type that are now used extensively in apartment houses and other dwellings in which the floor space is limited.

One type of disappearing bed that is now 15 in more or less general use is constructed in such a manner that it can be turned into a vertical position and swung into a closet adjoining the room in which the bed is used when it is desired to conceal the bed or arrange it in its inoperative position. Such a bed takes up considerable floor space in the closet, thus making it necessary to build the closet much larger than is actually necessary for the purpose of storing clothes in 20 the closet; it necessitates the use of clamping devices to clamp the bedding and the mattress to the bed spring, so as to prevent them from becoming displaced when the bed is arranged in a vertical or upright position; it is cumbersome and considerably 25 lower than an ordinary bed when it is arranged in operative position, and it is costly to manufacture and install, on account of its complicated design.

30 One object of my invention is to provide a disappearing bed which is so constructed that it occupies a horizontal position when not in use, and also when it is being moved into and out of operative position, thus over- 35 coming the necessity of using clamping devices for securing the bedding and the mattress to the bed spring.

Another object is to provide a disappearing bed that takes up no floor space when 40 not in use.

Another object is to provide a disappearing bed that presents the same appearance as an ordinary stationary bed when in use; that has standard height legs and in which 45 the operating mechanism is completely concealed from view, both when the bed is in use and not in use.

Another object is to provide a disappearing bed that can be moved easily into and 50 out of the compartment in which it is housed

when not in use, and which is so constructed that it can be arranged in a convenient position during the operation of making up the bed.

And still another object of my invention 60 is to provide a means by which an ordinary stationary bed can be easily converted into a disappearing bed. Other objects and desirable features of my invention will be hereinafter pointed out.

65 To this end I have devised a disappearing bed that comprises a bed which is preferably of the same size and design as an ordinary stationary bed, and mechanism for bodily lifting said bed into and out of a compartment located above the floor of the room in which the bed is used and connected with said room by an opening in one of the side walls of the room. The compartment in which the bed is housed when it is not in 70 use may be formed by the space in the upper portion of a single or double closet or by the space above an adjacent room whose ceiling is lower than the ceiling of the room in which the bed is used, and various means can 75 be used for moving the bed into and out of said compartment. The means that I prefer to use, however, consists of a counterweighted lever pivotally arranged in a vertical slot in one wall of the room in which the bed is 80 used and pivotally connected to said bed, means for turning said lever so as to move the bed into and out of the elevated compartment provided for same, and means for 85 holding the bed in a horizontal position 90 while it is being moved into and out of said compartment.

95 Figure 1 of the drawings is a view, partly in vertical section and partly in elevation, illustrating a disappearing bed constructed in accordance with my invention, showing the bed in operative position.

Fig. 2 is a similar view, showing the bed in its inoperative position.

Fig. 3 is a vertical sectional view, taken on 100 the line 3—3 of Fig. 1.

Fig. 4 is a view, taken on the line 4—4 of Fig. 1, showing the side wall of the room in elevation; and

Fig. 5 is an enlarged horizontal sectional 105 view, taken on the line 5—5 of Fig. 1.

Referring to the drawings, which illustrate the preferred form of my invention, A designates a bed, B designates the room in which the bed is arranged when it is in use, 110

and C designates a compartment arranged outside of said room and located in a higher horizontal plane than the floor of the room, said compartment C being connected with the room A by an opening in the side wall 1 of the room that is normally closed by a transom or hinged closure 2. The compartment C may either be located above a single or double closet D, or above an adjacent room whose ceiling is lower than the ceiling of the room B. In the form of my invention herein shown the compartment C is located above a double closet that is provided with a partition 3 in which a slot or pocket 4 is formed to receive the mechanism that moves the bed into and out of the compartment C, the front end of said slot communicating with a vertically-disposed slot 5 in the side wall 1 of the room B. It is immaterial, so far as my broad idea is concerned, what means is used for moving the bed into and out of the compartment C, but one efficient means that may be used for this purpose consists of a lever E arranged in the pocket in the partition 3 in the double closet D and rigidly connected to a horizontally-disposed shaft 6 that is journaled in said partition, as shown in Fig. 3, the lever E occupying the position shown in Fig. 1 when the bed is in use and the position shown in Fig. 2 when the bed is housed in the compartment C. The lever E is provided at its lower end with a forwardly-projecting arm 7 that is pivotally connected at 7^a to a transversely-disposed frame F arranged at the center of the bed below the bed spring, thus forming a substantially elbow-shaped lever whose arm 7 projects forwardly from the wall 1 when the bed is in use and which projects in the opposite direction from said wall, or, in other words, into the compartment C, when the bed is not in use, as shown in Fig. 2. Any suitable mechanism may be used for operating the lever E, the mechanism herein shown consisting of a crank arm 8 connected with a pinion 9 that meshes with a gear 10, which, in turn, is secured to the shaft 6 to which the lever E is rigidly connected, the rotation of the pinion 9 causing the lever E to turn on its axis. Means is provided for holding the bed A in a horizontal position while it is being moved into and out of the compartment C, which means preferably consists of an elbow-shaped lever G whose long arm is pivotally connected at 11 to the partition 3, and whose short arm is pivotally connected at 12 to the frame F on the bed. When the lever E is turned from the position shown in Fig. 1 to the position shown in Fig. 2, the lever G holds the bed in a horizontal position, as shown in broken lines in Fig. 1. In order to insure the lever G moving properly with relation to the movement of the lever E, I have provided said lever G at its upper end

with a sprocket wheel 13 which is surrounded by a sprocket chain 14 that travels over a sprocket wheel 15 on the shaft 6. When the lever E is turned on its fulcrum the sprocket chain 14 and the coöperating sprocket wheels 13 and 15 cause the lever G to move simultaneously at the same speed as the lever E, thereby eliminating the possibility of the bed A assuming other than a perfectly horizontal position while it is being moved into and out of the compartment C. If desired, the shaft to which the crank arm 8 and the pinion 9 are connected can be provided with a ratchet wheel 16 with which a ratchet 17 coöperates, so as to hold the lever E in a partially raised position, in case it is desired to have the bed raised slightly from the floor during the operation of making up the bed. The slot 5 in the side wall 1 of the room B is closed when the bed is in use by means of a flange 18 on one edge of the lever E that completely closes the upper portion of said slot and one-half of the lower portion of the slot, the remaining half of the lower portion of the slot being closed by a flange 19 on the lever G, as shown in Fig. 4. When the bed is not in use, or, in other words, arranged in the compartment C, the slot 5 is completely closed by a flange 20 on the other vertical edge of the lever E, said lever being preferably of the cross-sectional shape shown in Fig. 5. The lever E is preferably provided with a counterweight 21 arranged on same in such a position that very little power is required to swing the lever from the position shown in Fig. 1 to the position shown in Fig. 2, but said weight is so arranged that there is no liability of the bed A moving upwardly accidentally, when it is arranged in operative position, even though the mattress and all of the bed clothes are removed from the bed. The transom or hinged closure 2 of the compartment C is preferably operatively connected with the bed operating mechanism in such a manner that it will swing upwardly into the position shown in dotted lines in Fig. 1 while the bed A is traveling upwardly, and then back to its normal position to close the compartment C after the bed has entered said compartment. In the form of my invention herein shown this is effected by means of an arm 22 located adjacent the hinged upper edge of the transom and connected by means of a link 23 with an arm 24 on one end of a horizontally-disposed rock shaft 25 that is mounted in bearings on the floor of the compartment C, said rock shaft 25 being provided at its opposite end with an arm 25^a which is connected by means of a rod 26 with a cam on the gear 10 that causes the arm 24 to swing downwardly and then back to its normal position when the lever E is turned from the position shown in Fig. 1 into the posi-

tion shown in Fig. 2. The cam that I prefer to use is formed by a cam-shaped slot 27 in the gear 10 that receives a pin or roller 28 on the lower end of the rod 26, which cam slot is so shaped that the transom 2 will remain at rest during that period in the cycle of operations of the bed-operating mechanism when the bed is entering the compartment C. The frame F on the bed to which the levers E and G are connected is preferably provided at its ends with portions F' that are bolted or connected in any other suitable manner to the side rails of the bed, but it is of course immaterial, so far as my broad idea is concerned, how the bed and bed-operating mechanism are connected together.

A disappearing bed of the construction above described takes up no floor space when it is not in use, owing to the fact that it is housed in a compartment C formed by the waste space in a closet or by the space above a low-ceilinged room. Furthermore, such a bed requires no clamping devices to hold the bedding and the mattress on the bed spring, owing to the fact that the bed occupies a horizontal position when it is not in use and also when it is being moved into and out of the compartment C in which it is housed during the day. When the bed is in use it presents the same appearance as an ordinary stationary bed, as the bed-operating mechanism is completely concealed from view and the transom 2 remains in its closed position at such times. The bed-operating mechanism is of such design that very little power is required to move the bed into and out of the compartment C; and still another desirable feature of such a mechanism is that it can be locked by the pawl and ratchet 16 and 17, so as to hold the bed in a slightly raised position during the operation of making up the bed. The legs of the bed are of standard length and the other dimensions of the bed are preferably the same as those of an ordinary stationary bed. In fact, my invention makes it possible to convert an ordinary bed into a disappearing bed, by simply combining an ordinary bed with a bed-operating mechanism of the kind herein shown and locking the side rails and end pieces of the bed together in such a manner that they will not become detached when the bed is raised from the floor by said operating mechanism.

Having thus described my invention, what I claim, and desire to secure by Letters Patent, is:

1. A disappearing bed, comprising a bed, and an operating mechanism for said bed comprising a portion that projects through a vertical slot in one wall of the room in which the bed is used when the bed is arranged in operative position in said room, said mechanism being so constructed that

it can be operated to move said bed into and out of an elevated compartment located outside of said room.

2. A disappearing bed, comprising a bed, a vertically-disposed lever arranged in a slot or pocket that communicates with the room in which the bed is used, and an extension on said lever that is pivotally connected to said bed, said lever being adapted to be turned on its axis so as to move the bed into and out of a compartment arranged above the pocket in which the lever is housed.

3. A disappearing bed, comprising a bed, and an operating mechanism for said bed comprising a pair of substantially elbow-shaped levers arranged so that when they are moved in one direction they will raise the bed and move it into an elevated compartment and when moved in the opposite direction will withdraw the bed from said compartment and lower it to the floor of a room.

4. A disappearing bed, comprising a bed, an operating mechanism for said bed comprising a vertically-disposed member oscillatingly mounted in a pocket that communicates with a slot formed in one wall of the room in which the bed is used and provided with a portion that is pivotally connected to said bed, and means for turning said member on its axis so as to move the bed into and out of a compartment located above said member.

5. A disappearing bed, comprising a bed, an elevated compartment arranged outside of the room in which the bed is used and communicating with said room through an opening in one of the side walls of same and an operating mechanism arranged beneath the elevated compartment and connected to the bed for moving the bed into and out of said compartment, said mechanism being concealed from view except when moving the bed.

6. A disappearing bed, comprising a bed, a compartment for housing the bed when it is not in use located above a closet or low-ceilinged room adjacent the room in which the bed is used, a closure for said compartment that forms part of a wall of the room in which the bed is used, and an operating mechanism for said bed and closure constructed in such manner that the closure will open and close automatically when the bed is being moved upwardly into said compartment by said mechanism.

7. A disappearing bed, comprising a bed, a vertically-disposed lever arranged in such a position that it lies at one side of the bed when the bed is in use and provided with a forwardly-projecting portion that extends underneath the bed, means for turning said lever so as to raise the bed and deposit it in a compartment located above said lever,

and means for preventing the bed from turning out of a horizontal position when it is being moved by said lever.

8. A disappearing bed, comprising a bed, 5 a pair of substantially vertically-disposed levers pivotally connected to a supporting structure located outside of the room in which the bed is used and provided with angularly-disposed extensions that project into 10 said room through a slot in one of the side walls of same, said extensions being pivotally connected to the bed, and an elevated compartment located outside of the room in which the bed is used and into which the 15 bed can be moved by turning said levers.

9. A disappearing bed, comprising a bed, an elevated compartment in which the bed is housed when it is not in use, said compartment being located outside of the room 20 in which the bed is used, and a pivotally mounted operating mechanism for said bed, which, when rocked in one direction, withdraws the bed from said compartment and deposits it on the floor of said room.

25 10. A disappearing bed, comprising a bed, an elevated compartment arranged outside of the room in which the bed is used for housing the bed when it is not in use, a supporting structure beneath said compartment, 30 and a pair of substantially elbow-shaped levers on said supporting structure pivotally connected to said bed and adapted to be swung downwardly through a slot in one of the side walls of said room so as to withdraw the bed from said compartment and 35 deposit it on the floor of the room.

11. A disappearing bed, comprising a bed, an elevated compartment arranged outside of the room in which the bed is used, a 40 closure for said compartment, means for raising the bed from the floor of the room and depositing it in said compartment, and means for causing said closure to open and close automatically during the operation of 45 moving the bed from the room into said compartment.

12. A disappearing bed, comprising a bed, an elevated compartment arranged outside of the room in which the bed is used, a vertically-disposed, counterweighted lever oscillatingly mounted on a supporting structure beneath said compartment, an arm on said lever that is pivotally connected to said bed, said lever being adapted to be turned so as 50 to move the bed upwardly and deposit it in said compartment, and a slot in the side wall of the room through which said lever travels when it is moving the bed into and out of said compartment.

60 13. A bed-operating mechanism for the purpose described, comprising a vertically-disposed member oscillatingly mounted on a supporting structure and adapted to operate in a vertical slot formed in the side wall 65 of a room, and an angularly-disposed por-

tion on said member that is adapted to be pivotally connected to the bed with which the mechanism is used.

14. A bed-operating mechanism for the purpose described, comprising two substantially elbow-shaped levers pivotally connected to a supporting structure and adapted to operate in a vertical slot formed in the side wall of a room, the short arms of said levers being adapted to be pivotally connected to a bed. 70 75

15. A bed-operating mechanism, comprising a vertically-disposed, counterweighted member pivotally mounted on a supporting structure and having a portion that is adapted to be connected to a bed, means for turning said member on its axis so as to move the bed in an arcuate path, and means for maintaining said bed in a substantially horizontal position while it is being moved. 80 85

16. A bed-operating mechanism, comprising a vertically-disposed, counterweighted member pivotally mounted intermediate its ends on a supporting structure and provided on one end with an angularly-disposed arm, a substantially elbow-shaped lever pivotally mounted on said supporting structure, and a mechanism for causing said member and lever to move in unison. 90 95

17. A bed-operating mechanism, comprising a vertically-disposed member oscillatingly mounted on a supporting structure adjacent a vertical slot in the side wall of a room and provided at one end with a portion that is adapted to be pivotally connected to a bed, and means on said member that forms a closure for said slot. 100 105

18. A disappearing bed, comprising a bed, a transversely-disposed frame arranged underneath the spring of said bed, and an operating mechanism for said bed comprising two substantially elbow-shaped levers oscillatingly mounted on a stationary supporting structure and pivotally connected to said frame. 110

19. A disappearing bed, comprising a bed, an elevated compartment arranged outside of the room in which the bed is used, a pair of levers pivotally connected to said bed and operating in a vertical slot in the side wall of the room for raising and lowering the bed into and out of said compartment, and means on said levers that forms a closure for said slot when the bed is in use and when it is arranged in said compartment. 115 120

20. A disappearing bed, comprising a bed, an elevated compartment arranged outside of the room in which the bed is used, a pair of levers pivotally connected to said bed and operating in a vertical slot in the side wall of the room for raising and lowering the bed into and out of said compartment, means on said levers that forms a closure for said slot when the bed is in use and when it is 125

arranged in said compartment, a transom or closure for said compartment, a cam that turns when said levers move, and an operating mechanism for said transom actuated 5 by said cam.

21. A disappearing bed, comprising a bed, a counterweighted lever pivotally mounted on a supporting structure located outside of the room in which the bed is used and provided with a portion that projects through 10 a vertical slot in the side wall of the room when the bed is in use, an operating crank, a gear and pinion for transmitting movement from said crank to said lever, a locking mechanism for enabling said lever to be locked so as to hold the bed in a slightly elevated position, an elbow-shaped lever pivotally connected to said bed for preventing 15 it from moving out of horizontal position when it is being raised or lowered by said lever, and means for causing both of said levers to move in unison.

22. A disappearing bed, comprising a bed,

a counterweighted lever pivotally mounted on a supporting structure located outside of the room in which the bed is used and provided with a portion that projects through a vertical slot in the side wall of the room when the bed is in use, an operating crank, a gear and pinion for transmitting movement from said crank to said lever, a locking mechanism for enabling said lever to be locked so as to hold the bed in a slightly elevated position, an elbow-shaped lever pivotally connected to said bed for preventing it from moving out of horizontal position when it is being raised or lowered by said lever, and means for causing both of said levers to move in unison. 20 25 30
